UNITED STATES PATENT OFFICE.

HORATIO NELSON JACKSON, OF BURLINGTON, VERMONT.

RECEPTACLE.

1,217,948.

Specification of Letters Patent.

Patented Mar. 6, 1917.

Application filed May 5, 1916. Serial No. 95,651.

To all whom it may concern:

Be it known that I, HORATIO NELSON JACKSON, a citizen of the United States, residing at Burlington, in the county of Chittenden and State of Vermont, have invented 5 certain new and useful Improvements in Receptacles, of which the following is a specification.

This invention relates to receptacles and 10 more particularly to that class of such devices which are peculiarly adapted for pocket and personal use for holding tobacco in granular form, cigarette papers, matches and the like, and has for its object 15 the provision of a device of the character set forth which shall be compact, ornamental and especially adapted for the uses to which it is to be put.

With the foregoing and other objects in 20 view as will from time to time appear hereinafter this invention consists in the peculiar construction of a combination receptacle as described in the following specification and more particularly pointed out 25 in the appended claim.

Referring to the accompanying drawings illustrating the preferred embodiment of 30 this invention, and in which like reference characters indicate the same parts wherever used,

Figure 1 is a perspective view of the receptacle;

Fig. 2 is a longitudinal section therethrough and

Fig. 3 is a section on line 3—3 of Fig. 2.

The device comprises a casing 4 suitably curved to fit the pocket and provided with a centrally disposed partition 5 forming a compartment 6 and a second compartment 40 7 which latter is divided by a partition 8 into a pocket 9 having a bottom 10 and adapted to contain matches 11 and a space 12 for the reception of a book of cigarette papers or the like designated by the numeral 13.

Both the pocket 9 and the paper holding space 12 are open at their upper ends for the removal of the contents thereof, a cover 14 hinged at 15 and having a catch 16 adapted to engage a flange 17 being provided to protect the matches, etc., when the device is not in use and to lie flush with the outer wall of the casing 4 to present an unbroken appearance. Should it be desired to use the 55 cigarette papers, the book 13 may be with-

drawn upwardly from its receptacle 12, the cover 14 having been previously raised for the purpose.

The compartment 6 has an upper wall 18 carrying a threaded open extension 19 provided with a dispensing cap 20 of any suitable type.

A vertical partition 21 extends upwardly from the wall 18 and is of the same height as the partition 5 to which it is joined by 65 an extension 22 of the casing 4, a hinge 23 being mounted thereon to carry a second cover 24 similar to the cover 14 and adapted to inclose the cap 20, the cover 24 having a catch 25 adapted to engage a keeper 26 70 on a flange 27 upon the wall 18 and to lie flush with the casing wall 4.

It will be seen by the construction above described a receptacle is provided which forms a combination device for the holding 75 of smokers' essentials in such a manner as to fit the pocket of the user.

As many changes could be made in the above construction and many apparently widely different embodiments of my invention could be made, without departing from the scope thereof it is intended that all matter contained in the above description or shown in the accompanying drawings shall be interpreted as illustrative and not 85 in a limiting sense.

Having thus described my invention what I claim as new and desire to secure by Letters Patent is—

In a device of the character set forth the 90 combination with a casing, of a vertical transverse partition extending from the top to the bottom thereof, a horizontal partition provided with a filling opening extending from said first named partition, a second 95 vertical partition on said horizontal partition and parallel with said first vertical partition, a pivoted closure on each of said vertical partitions, a longitudinal vertical partition extending at right angles to said 100 first vertical partition and a second horizontal partition connecting said third vertical partition and the wall of the casing.

In testimony whereof I affix my signature in presence of two witnesses.

HORATIO NELSON JACKSON.

Witnesses:

ROBERT DALE,
S. HOLLISTER JACKSON.
